UNITED STATES PATENT OFFICE

DAVID KARRON, OF BROOKLYN, NEW YORK

MACHINE FOR MAKING FRAME PARTS FOR HAND BAGS

Application filed November 16, 1928. Serial No. 319,761.

This invention relates to a machine for making frame parts for handbags, and has for its primary object and purpose to provide certain improvements in a machine of this general type as disclosed in Patent No. 1,568,739, issued to me on the 5th day of January, 1926, whereby such bag frame parts of a predetermined cross sectional form may be expeditiously produced with a material improvement of the finished product.

In the machine shown in my issued patent, the stock is first acted upon by means of suitable dies to produce at spaced points in the length thereof integrally connected perforated ears by means of which assembled complementary frame members may be hingedly connected with each other. Thereafter the material is cut on a transverse line between the ears and the separated sections are successively bent into the desired cross sectional shape. This cutting of the sheet metal material between the connected ears, results in a rough or unfinished edge on the ear of each frame part, which it is desirable to eliminate. It is therefore, one of the important objects of my present improvements to provide a machine for forming the frame parts from sheet metal strip stock whereby this disadvantage is overcome and a perfectly finished product is produced.

It is also a further object of the invention to provide novel automatically acting means whereby the sheet metal frame parts are bent to provide an intermediate longitudinally extending channel or groove therein and longitudinal flanges extending to the walls of said groove in obtuse angular relation to each other.

With the above and other objects in view, the invention consists in the improved machine for forming bag frame parts and in the form, construction and relative arrangement of its several elements as will be hereinafter more fully described, illustrated in the accompanying drawings, and subsequently incorporated in the subjoined claims.

In the drawings, wherein I have illustrated one simple and practical embodiment of the invention, and in which similar reference

characters designate corresponding parts throughout the several views,

Figure 1 is a plan view of the sheet metal strip stock from which the frame parts are formed;

Fig. 2 is a transverse section taken on the line 2—2 of Fig. 1;

Fig. 3 is a view similar to Fig. 1 showing one edge of the sheet metal stock flanged;

Fig. 4 is a transverse section taken on the line 4—4 of Fig. 3;

Fig. 5 is a plan view illustrating the next operation, in which the stock is provided at spaced intervals with longitudinally separated ears with an integral connecting portion at one side of the ears;

Fig. 6 is a plan view showing a completely formed frame part;

Fig. 7 is a transverse section taken on the line 7—7 of Fig. 6;

Figs. 8 and 9 are vertical sectional views illustrating the stamping dies for performing the first operation to flange the edge of the strip as seen in Fig. 3;

Fig. 10 is a transverse sectional view through another part of the machine showing the sheet metal strip in position upon a movable anvil to be operated upon by the shaping die;

Fig. 11 is a fragmentary section on an enlarged scale showing the next step in the operation of the shaping or forming die;

Fig. 12 is a similar sectional view showing the final step in the operation of the machine, after the frame part has been bent or shaped;

Fig. 13 is a top plan view of the latter part of the machine;

Fig. 14 is a transverse sectional view taken on the line 14—14 of Fig. 13, and

Fig. 15 is a detail section taken on the line 15—15 of Fig. 14.

Referring in detail to the drawing, bag frame parts are formed from sheet metal strip stock indicated at 5 in Figs. 1 and 2 of the drawings which is of the required thickness so that it may be readily bent and shaped to the desired predetermined form.

In the first operation, the sheet metal strip 5 is provided along one of its longitudinal

edges with a continuous slightly inclined flange 6. This flanged strip is adapted to be fed over a suitable bed plate indicated at 7 having guiding means for the strip and above which a vertically movable die operates (not shown). This die, which produces at intervals in the length of the sheet metal strip the longitudinally spaced ears as shown at 8 is of slightly different form from that shown in my issued patent so that instead of providing the ears integrally connected with each other by a part of the stock, these ears have no direct connection and are completely separated at their opposed ends, the parts of the sheet metal strip at opposite sides of the ears do however, remain integrally joined at one side of the ears 8 by the narrow longitudinally extending connecting portion 9. Each of the ears 8 is of course, perforated as at 10 to receive the usual hinge pin when assembled complementary frame members are connected with each other.

After the metal strip has been provided with the ears 8 and connecting portion 9, it is fed over a table 11 having suitable guiding means and upon a supporting flange 13 of an anvil 12, the length of which is substantially equivalent to the length of one of the frame parts. This anvil is pivotally mounted for vertical movement as shown at 14 upon a suitable support 15 transversely spaced from the table 11 and is yieldingly urged upwardly by means of the springs 16 into engagement with the stop rod 17. This anvil is provided with a longitudinally extending flange 18 projecting upwardly above the supporting flange 13 upon which one edge portion of the metal frame strip is received.

Above the table 11 and the anvil 12, there is arranged a vertically movable plunger 19 which carries a die plate 20 having a lower edge portion 21 of the proper cross sectional shape for bending the frame parts into the form shown in Figs. 6 and 7 of the drawings. Any suitable means may be provided for moving this plunger downwardly against the action of the springs indicated at 22 which normally hold the die plunger in a raised position. The plunger 19 also carries a part 23 having a beveled surface 24 to cooperate with a correspondingly beveled surface 27 on the upstanding flange 26 provided upon one edge of the plate 25 which is slidably mounted in suitable guide ways on the under side of the table 11. At its other edge this transversely slidable plate may be provided with suitable supporting legs 28 resting on a base 29. Coiled springs 22 normally hold plate 25 in the position shown in Fig. 10 of the drawings, and in spaced relation to the anvil 12 and its support 15.

At the right hand end of the plunger 19, a vertically movable member 31 is suitably pivoted at one of its ends as at 32, the other end of said member being provided with a

downwardly extending finger 33 and being yieldingly held by means of the leaf spring 34 in contact with a stop 35. With this latter end of the member 31 a projecting part on the manually operated plate 36 which is pivotally supported intermediate of its ends as at 37 is engaged. By depressing the other end of this plate, the end of the member 31 having the part 33 may be lifted against the action of spring 34 to the dotted line position as shown in Fig. 14 of the drawings. This displacement of the part 31 is made with each feeding movement of the sheet metal strip so as to position the spaced ears 8 and the connecting portion 9 of said strip with respect to a vertically movable cutting member 38 which may be mounted upon the right hand end of the plunger member 19 so as to operate with the die plate 20.

Assuming that the section of the metal strip which has previously been operated upon to provide the ears 8 and the connecting portion 9 therein is disposed in the position shown in Fig. 13 and one section of the strip is positioned on the part 13 of the anvil 12 as shown in Fig. 10, upon lowering the plunger 19, the lower edge thereof comes into bearing contact upon the strip section and at the same time its lateral side face bears against the face of the upstanding flange 18 on the anvil so that in the continued downward movement of the die plate 20, the anvil and the strip section move as a unit therewith until the anvil engages the upper surface of the support 15. In this operation, the camming action between the beveled surfaces 24 and 27 causes an inward movement of the plate 25 beneath the opposite edge portion of the sheet metal strip section to the position substantially indicated in Fig. 11. At this time, the knife 38 operates to cut out the narrow portion 9 of the sheet metal strip at the right hand end of the die plate 20 and thus separate the section which is positioned upon the anvil 12 and the plate 25 from the remaining part of the strip. As the die plate 20 now continues its downward movement and the plate 25 simultaneously moves inwardly beneath said strip section towards the anvil 12, the lower edge of the die plate forces the intermediate part of the sheet metal strip section downwardly throughout the length of said section between the flange 13 of the anvil and the opposed edge of the plate 25, thereby producing the longitudinally extending channel 39 in the frame part. The shoulder 21' of the die plate 20 bears upon one edge portion of the frame part at one side of the channel 39 forcing the same upon the surface of the flange 13 while the edge of the table 25 constitutes a fulcrum against which the opposite edge portion of the frame part bears so that in the movement of said plate, it is forced upwardly against the obliquely

inclined surface 21^a of the die plate. There is in this manner provided the frame part having flanges 40 and 41 at opposite sides of the channel 39 which extend in obtuse angular relation to each other, the projecting ears 8 constituting integral extensions of the flange 41.

When the die plate 20 is raised, the plate 25 and the anvil 12 return to their normal positions, and in the upward movement of the anvil 12, the formed frame part is dislodged and drops downwardly between the support 15 and the table 11, as shown in Fig. 12 of the drawings. The stock is then fed from table 7 over table 11 and upon the anvil 12 until another pair of the ears 8 is positioned as shown in Fig. 13. Pressure on the plate 36 is then released so that member 31 is forced downwardly by the spring 34 and the part 33 of said member enters between the opposed spaced ears 8, thus preventing any longitudinal shifting movement of the strip during the operation of the shaping die 20 and the cutting die 38 so that the accurate cutting out or removal of the connecting portion 9 between the sections of the sheet metal strip is assured, whereby a perfectly finished product will be obtained.

From the foregoing description, considered in connection with the accompanying drawings, it will be seen that I have devised a machine for very rapidly and accurately producing such sheet metal frame parts for ladies' hand bags and the like. It is of course understood that in the use of these frame parts, the material constituting the body wall of the bag is connected with the flanges 41 of the complementary frame sections while the other flanges 40 abut against each other when the bag is closed. It will further be understood that these frame parts may be bent or shaped as desired by other operations in accordance with the particular outline form of the bag.

It will be seen that by means of my present improvements, the edges of the ears provided at the ends of the frame parts are entirely smooth and unbroken so that no subsequent additional operations are necessary in order to properly finish these ends of the frame parts. The form and arrangement of the several cooperating elements as above described also insures the positive and reliable operation of the mechanism whereby perfect uniformity in the resultant product is obtained.

I have herein shown an embodiment of the invention, which has given very satisfactory results in practical operation. Nevertheless, it is to be understood that the essential features of my present improvements might also be incorporated in various other alternative mechanical structures, and I accordingly reserve the privilege of resorting to all such legitimate changes therein as may

be fairly incorporated within the spirit and scope of the invention as claimed.

I claim:

1. A machine of the character described comprising supporting and guiding means for sheet metal strip stock having sections integrally connected along one edge of the strip and spaced apart ears projecting from the opposed ends of said sections, means for cutting out said connecting edge portion of the strip to separate an end section from the strip, manually displaceable means interposed between the spaced ears to prevent longitudinal movement of the strip during the cutting operation, and means for bending said separated section throughout its length into predetermined cross sectional form. 70

2. In a machine for forming frame parts for hand bags, supporting means for a sheet metal strip having ears projecting from its opposite ends, said supporting means including a transversely movable part constituting a shiftable fulcrum for the strip and a vertically movable anvil spaced from said part and yieldingly supported above the plane thereof to sustain the strip out of contact with said part, a vertically movable plunger mounted above the supporting means, a die plate formed to coact with the anvil and to depress the same from its normal position and engage the sheet metal strip upon said transversely movable part, means for actuating said part in the operative movement of said plunger whereby 90 under the pressure of the die plate and in cooperation with the parts of said support, the sheet metal strip is shaped or formed to provide flanges extending in obtuse angular relation to each other at opposite sides 100 of an intervening longitudinal channel. 105

3. In a machine of the character described, supporting means for a sheet metal strip including a vertically yieldable part upon which one edge of the strip is adapted to rest, and a transversely shiftable part movable beneath the other edge of the sheet metal strip, a shaping die vertically movable above said vertically movable supporting part and adapted to coact therewith to depress the same and engage the sheet metal strip upon said transversely movable part, and means for moving the latter part inwardly in contact with the under side of the sheet metal strip during downward movement of 110 the shaping die to coact with the latter and bend said strip into predetermined cross sectional shape or form. 115

4. In a machine of the character described, a vertically movable support, and a transversely movable member spaced therefrom, said support being adapted to receive one edge of a sheet metal strip and sustain said strip with its other edge disposed above and in spaced relation to said transversely mov- 125 130

able member, a vertically movable die adapted for initial engagement upon said first named edge of the metal strip and cooperating with said vertically movable support to move the same downwardly and engage the other edge of said strip with said member, and means for simultaneously moving said member inwardly towards said support to bend the latter edge of the sheet metal strip upwardly against the die, and said die having parts cooperating with said movable support and member to bend the sheet metal strip into predetermined cross sectional form.

15 In testimony that I claim the foregoing as my invention, I have signed my name hereto.

DAVID KARRON.
